UNITED STATES PATENT OFFICE.

HARRY S. ADAMS AND GEORGE F. WAGENER, OF YOUNGSTOWN, OHIO.

REINFORCED-CONCRETE TIE.

1,147,132.

Specification of Letters Patent. Patented July 20, 1915.

Application filed March 13, 1915. Serial No. 14,141.

To all whom it may concern:

Be it known that we, HARRY S. ADAMS and GEORGE F. WAGENER, citizens of the United States, residing at Youngstown, in the county of Mahoning and State of Ohio, have invented certain new and useful Improvements in Reinforced-Concrete Ties; and we do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in concrete ties and consists of a simple and efficient device of this nature having various details of construction, combinations and arrangements of parts which will be hereinafter fully described, shown in the accompanying drawings and then specifically defined in the appended claim.

Our invention is illustrated in the accompanying drawings, in which:

Figure 1 is a central vertical section through a tie made in accordance with our invention showing the rail in cross section held thereto. Fig. 2 is a transverse sectional view through the tie.

Reference now being had to the details of the drawings by letter, A designates a tie made up of concrete and in which are embedded series of rods B, and C designates a plate upon the top of the tie to which the rail D is held by means of the plates E which are apertured for the reception of the bolts F. Said concrete tie has embedded therein a horizontally disposed apertured plate H having apertures H' therein, and angle plates I with bolt apertures I' in the apex thereof and which apertures I' are in registration with the apertures H' in the

plate H. Rods B are embedded in the concrete, two opposite the lower ends of the angle plate and the upper two opposite and spaced apart from the opposite edges of the plate H, and a wire N is wound about the several rods B and pass underneath and forms a support for the lower ends of the angle plate I and also a transverse portion of the wire engages underneath and forms a support for the plate H. Said bolt has a head F' which, when adjusted in place, occupies the space between the walls of the angle plate I and in the countersunk hole S formed in the bottom of the tie, while its upper portion passes through an aperture in the plate C and is adapted to receive the nut T. In adjusting the parts in place, it will be noted that the tie is so constructed that the bolt may be slipped through the tie and through the apertures in the two plates and held in a locked relation by means of the nut and by which construction the bolt may be readily removed when desired by reason of the peculiar construction shown and described.

What we claim to be new is:—

A reinforced concrete tie having an angle plate embedded near the lower portion of the tie and a flat plate in the tie above said angle plate, said plates provided with registering apertures, a bolt passing through said apertures and having a head engaging the walls of the angle plate and positioned intermediate the same, rods embedded in the tie, and a wire passing about said rods and engaging said plates.

In testimony whereof we hereunto affix our signatures in presence of two witnesses.

HARRY S. ADAMS.
GEORGE F. WAGENER.
